UNITED STATES PATENT OFFICE.

DAMASO RIVAS, OF PHILADELPHIA, PENNSYLVANIA.

BOTTLE AND STOPPER THEREFOR.

No. 877,229.

Specification of Letters Patent.

Patented Jan. 21, 1908.

Application filed August 5, 1907. Serial No. 387,017.

To all whom it may concern:

Be it known that I, DAMASO RIVAS, a citizen of the United States, residing at the city of Philadelphia, in the county of Philadelphia and State of Pennsylvania, have invented certain new and useful Improvements in Bottles and Stoppers Therefor, of which the following is a specification.

My invention has relation to a bottle provided with an air and fluid tight stopper, the bottle being adapted particularly for collecting water and other fluids for bacteriological examinations; and in such connection it relates to the constructive arrangement of the bottle and stopper so that the fluid contents may be thoroughly protected against extraneous elements or floating germ life to adapt the bottle especially for collecting fluids in the making of bacteriological examinations.

The nature and characteristic features of my invention will be more fully understood from the following description taken in connection with the accompanying drawings forming part hereof, in which

Figure 1, is a vertical central sectional view of a bottle with a stopper embodying, respectively, main features of my invention. Fig. 2, is a perspective view of the stopper removed from the bottle, showing detailed arrangement thereof; and Fig. 3, is an elevational view of the bottle, showing the particular arrangement of the neck of the bottle adapted to fit the stopper of my invention, as shown in Fig. 1, thereto to render the fluid contents of the bottle air tight and thereby proof against entrance of extraneous matter or floating germ life to such contents, while the bottle is stoppered.

Referring to the drawings 4, is the bottle of glass in shape round, oblong or square and having preferably a tapering neck 5, with an upper projection forming a flange 6, and an intermediate projection forming a circular seat 7, as clearly illustrated in Fig. 1, for a purpose to be presently more fully explained. 8, is the stopper of glass or other hard gritty material having a solid tapering body 9, adapted to snugly fit the inner wall of the neck 5, the upper portion of which is provided with a projection forming a flange 10, for engaging the fingers therewith so as to permit of ready turning of the stopper in the neck of the bottle and projecting downwardly from the flange 10, is provided preferably a conical shaped wall 11. The depending wall

11, tapers in an opposite direction to the body 9, of the stopper fitting the neck of the bottle and arranged to seat with the projection 7, to render the stopper in its connection with the bottle air and fluid tight so as to especially adapt the bottle for the collecting of fluids in the making of bacteriological examinations, because the contents is thoroughly protected against the influence of extraneous matter or floating germ life. Moreover, the stopper having two points of bearing contact with projections 6 and 7, of the bottle 4, prevents any possibility by capillary attraction of foreign elements or fluids gaining access to the interior of the bottle, stoppered. The bottle as so arranged is easily stoppered as well as permits of ready discharge of the fluid contents. Around the stopper 8, is applied a fibrous or other material forming an envelop or closure 12, adapted to be drawn around the depending tapering wall 11, of the stopper and crimped or folded into a contracted form about the base of the neck 5, and around which is passed a wire 13, provided with a designation tag 14, as illustrated in Fig. 3. The closure 12, is adapted to envelop the stopper in such a manner as to thoroughly guard or protect the same against tampering with the contents of the bottle, when filled and sealed, as at 15, and the tag is intended for containing matter to show an analysis of the contents of the bottle thus sealed.

Having thus described the nature and objects of my invention what I claim as new and desire to secure by Letters Patent is:

1. A bottle provided with a neck having a projection forming a seat, and a stopper provided with a tapering body fitting the bottle-neck and having a depending wall tapering in an opposite direction to said body adapted to seat with the projection of the bottle-neck, substantially as and for the purposes set forth.

2. A bottle provided with a neck having a projection forming a seat and a stopper having a body fitting the interior of the neck and having a flaring wall adapted to seat with the projection of the bottle-neck, substantially as and for the purposes set forth.

3. A bottle provided with a neck having a projection forming a seat, a stopper fitting the bottle-neck and having a depending tapering wall adapted to seat with the projection of the bottle-neck and a closure or envelop for said stopper adapted to be secured

to the bottle-neck, substantially as and for the purposes set forth.

4. A bottle provided with a neck having a projection forming a seat, a stopper fitting the bottle-neck and having a depending wall adapted to seat with the projection of the bottle-neck, a closure or envelop for said stopper and means for securing and sealing the closure or envelop to said bottle, sub-

stantially as and for the purposes set forth. 10

In testimony whereof, I have hereunto set my signature in the presence of two subscribing witnesses.

DAMASO RIVAS.

Witnesses:

THOMAS M. SMITH,
GENEVIEVE M. CONNERTON.
